The ornamental design for an electric irrigator, as shown and described.

DESCRIPTION

FIG. 1 is a front, top perspective view of an electric irrigator, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail “9” identified in FIG. 1; and,

FIG. 10 is an enlarged view of detail “10” identified in FIG. 1.

The dashed broken lines in the figures illustrate portions of the electric irrigator that form no part of the claimed design. The dash-dot-dash broken lines in FIGS. 1, 9 and 10 depict the bounds of the enlarged views and form no part of the claimed design.
